UNITED STATES PATENT OFFICE.

LAURA LEGGETT DOOLITTLE, OF NEW HAVEN, CONNECTICUT.

DESIGN FOR A PAPER-WEIGHT AND TIMEPIECE.

41,554.

Specification for Design.

Patented July 11, 1911.

Application filed December 20, 1909. Serial No. 534,218. Term of patent 7 years.

To all whom it may concern:

Be it known that I, LAURA LEGGETT DOOLITTLE, a citizen of the United States, residing at New Haven, in the county of New Haven and State of Connecticut, have invented a new, original, and ornamental Design for a Paper-Weight and Timepiece, of which the following is a specification, reference being had to the accompanying drawing, forming part thereof.

As shown in the drawing, my design comprehends two transparent bell-shaped bodies *a a* having their smaller ends united and communicating and provided at their larger ends with rigid projecting portions *b* representing bell-clappers, said projecting por-

tions being also rigid with two heads *c c* between which the two bell-shaped bodies *a a* are disposed, and posts *d d* extend from one head to the other at respective sides of the bell-shaped bodies *a a*.

The figure is a view in elevation of a paper weight and time piece, showing my new design.

I claim:

The ornamental design for a paper weight and time piece, as shown.

LAURA LEGGETT DOOLITTLE.
